(57) **CLAIM**

The ornamental design for an accessory for a desk, as shown and described.

DESCRIPTION

FIG. 1 is a perspective view of the accessory for a desk, showing our new design;

FIG. 2 is a rear view thereof and

FIG. 3 is a front view thereof;

FIG. 4 is a left side view thereof and

FIG. 5 is a right side view thereof; and

FIG. 6 is a top view thereof; and,

FIG. 7 is a bottom view thereof.

The accessory for a desk is shown with two symbolic breaks in its length. The appearance of any portions of the article beyond the break line forms no part of the claimed design. In addition, the broken lines in the drawings represent portions of the accessory for a desk and form no part of the claimed design.
